SASH BALANCE

Albert J. Rosentreter, Bownton, N. J., assignor to
Rochester Sash Balance Co., Inc., Rochester,
N. Y., a corporation of New York

Application December 9, 1940, Serial No. 369,240

5 Claims. (Cl. 16—197)

This invention relates to a sash balance, with particular reference to the style of construction that employs a spring tension element, and it has for its object to provide simple and practical means of economical construction for locking the spring element in predetermined position after it is tensioned or wound at the factory, such locking means being released automatically after the device is installed in a sash in operative position upon the raising or lowering of the sash, thus assuring under operating conditions the tension given the spring when the structure is made and assembled at the factory.

Devices have been heretofore proposed for the pretensioning of springs in sash balances of this general character, but in such instances, the usual procedure has been for the workman who installs the sash balance to remove a locking instrumentality after the parts are in operative relation, and the objection to this arrangement is that it frequently happens that the removal of the locking device is neglected or forgotten, resulting in the inoperativeness of the balance and dissatisfaction with the mechanism.

To overcome this, it is proposed according to the present invention to provide a spring sash balance with a locking device that is arranged in locking position by the factory assembler after the spring has been wound to the desired extent, and remains in such locking position until the device is installed and ready for operation, whereupon movement of the sash automatically displaces the locking member, either by gravity or otherwise after it is released, and thereafter the sash balance continues to operate under the predetermined spring tension, there being no further function of the locking instrumentality unless it becomes necessary to remove the balance from the sash and again wind the spring.

The invention has for its further object to afford certain simplified, economical and efficient structural features in a spring sash balance of the type generally characterized by a rotatable spiral or twisted bar carried by the movable sash and having a coil spring wound therearound and retained in the convolutions of the spiral bar, the spring being under tension and acting to hold the bar and window in any position of adjustment.

More particularly, the invention has for a further object to afford simple, practical, and efficient means for securing together such a spiral bar and spring and for mounting the spring and spiral bar upon suitable supporting plates

which are attachable to a sash, these parts being designed to afford economy of construction and to facilitate the assembly and installation of the parts.

To these and other ends, the invention consists in the construction and arrangement of parts that will appear clearly from the following description when read in conjunction with the accompanying drawing, the novel features being pointed out in the claims following the specification.

In the drawing:

Fig. 1 is a view in front elevation, partially in section, illustrating a preferred embodiment of the invention as applied to a window sash and frame;

Fig. 2 is a vertical sectional view on the line 2—2 of Fig. 1, showing the locking member in its upper or locking position, holding the spiral bar with the spring under tension;

Fig. 3 is a similar view showing the locking member in lowered position, with the spiral bar and spring released;

Fig. 4 is a horizontal sectional view on the line 4—4 of Fig. 2;

Fig. 5 is a perspective view of the upper supporting plate upon which the spring and spiral member are mounted, and

Fig. 6 is a perspective view of the lower fastening plate in which the spring and spiral member are journaled at their lower ends.

The subject matter of this application is in the nature of an improvement on the construction disclosed in my application filed July 15, 1940, Serial No. 345,489, patent issued February 4, 1941, No. 2,230,763, and referring more particularly to the drawing in which like reference numerals refer to the same parts throughout the several views, 1 designates a window sash slideable within a frame 2, and mortised at its edges to receive the mechanism to be described. The structure includes supporting means in the form of a fastening plate 3 that is rigidly secured to the upper end of the sash with its outer end

overlying the mortised portion in the side of the sash, said outer end including a depending portion 4 and a horizontal supporting plate 5 that is slotted at 6 to receive and support the controlling spring and rotatable spiral member carried thereon, while 7 designates upstanding lateral flanges for a purpose that will appear presently.

The rotatable member consists of a twisted or spiral bar 8 which is rotatably mounted in relation to the supporting means already de-

scribed, and so associated with a coil spring 9 as to place the same under tension when the spiral bar is moved endwise and thereby rotated upon movement of the sash. Preferably this relationship is effected by mounting the spiral bar 8 upon the coil spring 9 as shown, by providing a right-angled or lateral portion or lug 10 at the upper end of the spiral bar, said lug 10 being provided with an opening through which the spring 9 extends, the spring thus affording a bearing for the rotatable spiral bar.

Beneath the lug 10, the coil spring 9 is twisted around the spiral bar 8 following the convolutions thereof, and at the lower end of the bar, the coil spring is bent laterally to afford an offset terminal portion 11 that receives a lug 12 at the end of the spiral bar 8, thus holding the lower ends of the spiral bar and spring in rigid relationship while permitting relative turning of the upper end of the spiral bar on the spring.

The lower terminal portion 11 of the spring is journalled in a bearing carried by the sash, said bearing preferably including an attaching plate 13 having prongs 14 which are driven into the sash, a vertical portion 15 and a lateral bearing plate 16 having a curved edge 17 engaging a corresponding groove in the mortised portion of the sash. The bearing plate 16 is provided with an opening 18 that receives the terminal portion 11 of the coil spring and serves as a centering bearing therefor, the bottom of said terminal portion 11 and the bottom of the lug 12 of the spiral bar being somewhat above and in spaced relation to the fastening plate 13.

The coil spring 9 has attached to its upper end a nut or hollow squared head 21 to which the spring may be rigidly attached in any desirable manner as by a pin 22 driven into the coil spring and holding the latter firmly between it and the surrounding surface of the squared head 21. The entire assembly including the spiral bar and spring is mounted upon the supporting plate 5 by sliding the spring laterally through the slot 6 with the nut or squared head 21 located above the supporting plate 5, and between the upstanding lugs 7 which hold the squared head 21 in position and prevent its rotation when the spiral bar is rotated and the spring thereby twisted.

The spiral bar is adapted to be rotated in any suitable fashion when the sash is moved, and this may be accomplished conveniently by a plate 23 or other suitable means permanently attached to the window frame and carrying lugs 24 that embrace the opposite edges of the spiral bar 8, causing the latter to be rotated in one direction or the other as the sash is raised or lowered.

Thus as the sash and mechanism mounted thereon moves upwardly or downwardly, the spiral bar 8 is rotated by the lugs 24 on the stationary plate 23, and since the spiral bar is fixed at its lower end to the coil spring 9 while the upper end of the coil spring is fixed against rotation on the supporting plate 5, the spring is stretched and its tension increased as the sash moves in one direction. The tension of the spring acting on the spiral bar and tending to rotate the latter to its initial position, holds the bar in frictional engagement with the lugs 24 with sufficient force to retain the window in any position to which it is moved, and there is always sufficient tension of the spring to hold the sash at any given point in its vertical travel.

In order to facilitate the installation of such a spring balance and to insure its proper oper-

ation after installation, it is desirable to turn the spiral bar and thereby tension the spring to a predetermined extent at the factory when the structure is made and assembled and to maintain the spring by suitable locking means under such predetermined tension imparted to it at the factory until it is completely installed and ready for use. According to the present invention, after such installation, upon movement of the sash the locking means by which the spring has been held in its pretensioned condition is automatically released.

This may be accomplished in various ways and preferably, as shown in the present embodiment, by a locking member that is movably mounted upon the spiral bar and actuated to its unlocking position by gravity. To accomplish this, there is preferably employed a locking member in the form of a slidable keeper 26 having flanges 27 embracing the straight portion at the upper end of the spiral bar 8 and permitting the keeper 26 to slide thereon, while 28 is a locking portion movable through the slot 6 in the supporting plate 5 and having a nose 29 adapted to engage over the upper surface of said supporting plate 5 adjacent to the slot 6 to hold the locking member in its uppermost or locking position, as shown in Fig. 2. 31 is a cam surface on the locking portion that is engaged by the edge of slot 6, when the spiral bar is turned, and positively moves the keeper downwardly to release the parts if the action of gravity is not sufficient for the purpose.

It will be understood that when released, the locking member moves downwardly until it reaches the twisted or spiral portion of the bar where it is retained in its lowered or unlocking position illustrated in Fig. 3, and the spiral bar can be rotated and the spring tensioned to any extent desired, while the locking member remains in such lowered position. When the spring has been tensioned to the proper degree, as determined by factory standards, the spiral member is turned further until the locking member is opposite the slot 6, as shown in Fig. 3, whereupon the operator manually slides the keeper upwardly until the portion 28 and nose 29 are within the slot 6 and above the supporting plate portion 5. Then upon releasing the spiral bar, the nose 29 of the locking portion engages the adjacent surface of the supporting plate 5, as shown in Fig. 2, and holds the spiral bar in such position with the spring under the tension already imparted to it.

The parts remain in this position, and there is no necessity for the workman who installs the balance to do anything about tensioning the spring, since when the parts are secured in operative position, upon raising or lowering the sash from its initial position, additional tension is placed on the spring and the spiral bar is turned slightly and sufficiently to move the locking member from the position of Fig. 2 slightly to the right where the nose 29 of the locking portion is free. Thereupon the locking member falls by gravity, or is actuated by the engagement of cam surface 31 with the edge of the slot 6 in advance of its movement, to the position shown in Fig. 3, and has no further function to perform while the balance remains installed and in operation. The spring then continues to function under the tension established for it at the factory.

It will be understood that if it becomes necessary to remove the balance, to repair or replace

any of the parts, the spring is again tensioned and the locking member placed in locking position to hold the spiral bar and spring until after the device is again secured to the sash in operative relationship, whereupon the locking member is automatically released upon movement of the sash.

While the invention has been described with reference to the structural details disclosed, it is not confined to this particular embodiment, and the application is intended to cover any modifications or departures coming within the purposes of the improvement and the scope of the following claims.

I claim:

1. A sash balance construction comprising a spiral bar vertically and rotatably positionable on a sash, a coil spring connected to said rotatable spiral bar and controlling its movement, and locking means positionable to engage the rotatable spiral bar with a stationary part and hold the spring and rotatable spiral bar in predetermined relation, said locking means being slidable on the spiral bar, and means acting automatically to engage and move the locking means on the spiral bar to free the rotatable spiral bar and spring upon movement of the sash to which the parts are attached.

2. A sash balance construction comprising a spiral bar vertically and rotatably positionable on a sash, a coil spring connected to said rotatable spiral bar and controlling its movement, locking means positionable to engage the spiral bar with a stationary part and hold the spring and spiral bar in predetermined relation, said locking means being slidable on the spiral bar and movable downwardly automatically to unlocking position when the sash to which the parts are attached is moved, and means acting automatically to engage and move the locking means on the spiral bar to free the rotatable spiral bar and spring upon movement of the sash.

3. A sash balance construction comprising supporting means, a spiral bar rotatably suspended from the supporting means, a coil spring which lies lengthwise along the spiral bar bodily, conforming to the convolutions thereof and having its upper end secured in fixed relation to the supporting means and its lower end fixed to said spiral bar, an actuator positionable in relatively fixed relation for engagement with the spiral bar and acting to turn the latter when relative endwise movement is effected between the spiral bar and actuator, locking means movably mounted at the upper end of the spiral bar and engageable with a portion of the supporting means for holding the spiral bar and spring under predetermined tension, said locking means being movable downwardly and automatically released from locking position when the spiral bar is turned by movement of the sash to which it is

attached, and means acting automatically to engage and move the locking means on the spiral bar to free the rotatable spiral bar and spring upon movement of the sash.

5. A sash balance construction comprising supporting means, a spiral bar rotatably suspended from the supporting means, a coil spring which lies lengthwise along the said spiral bar bodily conforming to the convolutions thereof and having its upper end fixed to the supporting means and its lower end fixed to the adjacent end of said spiral bar, an actuator positionable in relatively fixed relation for engagement with said spiral bar and acting to effect rotation thereof upon relative endwise movement between the spiral bar and the actuator, locking means slidably mounted at the upper end of the spiral bar and engageable when in its uppermost position with a portion of said supporting means for holding the spiral bar and spring under predetermined tension, said locking means being automatically movable downwardly to unlocking position when the spiral bar is rotated upon movement of the sash to which it is attached, and means acting automatically to engage and move the locking means on the spiral bar to free the rotatable spiral bar and spring upon movement of the sash.

15. A sash balance construction comprising supporting means including a plate slotted at one edge and having upstanding flanges adjacent to said slot, a coil spring extending through said slot and fixedly carrying a head located on said plate between said upstanding flanges and held against rotation thereby, a spiral bar having a laterally extending end portion located under said plate and journaled on said spring, the portion of the spring below said end portion of the bar lying lengthwise along the spiral bar bodily conforming to the convolutions thereof and having a terminal portion at its lower end offset from the body of the spring, a lug at the lower end of the spiral bar engaging said terminal portion of the spring, an actuator positionable in relatively fixed relationship to the spiral bar and acting to effect rotation thereof when relative endwise movement is effected between the spiral bar and the actuator, a locking member slidably mounted on said spiral bar and having a locking portion movable through the slot in said plate and engageable with the latter to hold the spiral bar against rotation, the locking member being downwardly movable automatically upon the spiral bar to unlocking position when the spiral bar is turned upon vertical movement of the sash to which it is secured, and means acting automatically to engage and move the locking member on the spiral bar to free the rotatable spiral bar and spring upon movement of the sash.

ALBERT J. ROSENTRETER.
